UNITED STATES PATENT OFFICE.

ALLAN L. McGREGOR, OF CHICAGO, ILLINOIS.

SHOCK-ABSORBER.

1,279,566.

Specification of Letters Patent. Patented Sept. 24, 1918.

Application filed December 20, 1916. Serial No. 137,932.

To all whom it may concern:

Be it known that I, ALLAN L. McGREGOR, a citizen of the United States, and a resident of Chicago, in the county of Cook and State of Illinois, have invented certain new and useful Improvements in Shock-Absorbers, of which the following is a specification.

My invention relates to shock absorbers which are used in connection with vehicles 10 to prevent violent reaction of the vehicle springs and to gradually absorb the forces to prevent shocks.

There are a great many devices on the market intended for this purpose but they 15 are more or less complicated and expensive. The object of my invention is to provide a simple, inexpensive and reliable device which will effectively and efficiently prevent sudden and violent separation between spring 20 members or between the vehicle frame and the springs and which will gradually absorb the forces occasioned by the tendency of such separation.

On the accompanying drawing I disclose 25 a device embodying the various features of my invention. On the drawing—

Figure 1 is a side elevational view of the device applied to a vehicle frame and axle, part of the device frame-work being shown 30 in section,

Fig. 2 is a plan view, and

Fig. 3 is a sectional view on plane 3—3, Fig. 1.

The device body is of general circular or 35 elliptic shape and comprises a drum 5 from which laterally extend side plates 6 and 7 for supporting upper and lower pins 8 and 9 on which rollers 10 and 11 are journaled between the plates. Located diamet- 40 trally in the drum and in horizontal position, as shown, is the barrel 12 for the compres- sion spring 13, the barrel, drum and roller supporting plates being preferably part of an integral casting. The spring encircles a 45 rod 14 which extends into the barrel through the opening 15 in the outer abutment wall 16, the spring being confined between the wall and the abutment washer 17 held on the inner end of the rod by the nuts 18. 50 The outer end of the rod is detachably se- cured to a strap or belt 19 of suitable ma- terial, which strap passes around the lower roller 11, then around the drum 5, then over the top roller 10. Below the spring barrel 55 are two transversely extending lugs 20 and 21 for bolts 22 and 23 by means of which a

bracket 24 is secured to the device frame- work, this bracket having a slot 25 for re- ceiving one of the flanges of the side beam 26 of the vehicle frame, set screws 27 de- 60 tachably securing the bracket to the vehicle frame and supporting the absorbing device in vertical position at the vehicle side above the vehicle axle 28, a similar absorbing de- 65 vice being placed at the opposite side of the vehicle. After the belt or strap 19 passes over the top roller 10 it extends downwardly and terminates in a loop 29 which receives the axle. To hold the strap to the drum re- 70 taining flanges 30 and 31 are provided and connected by cross-pieces 32.

When the shock absorber devices are ap- plied to a vehicle the straps are preferably given a primary tension sufficient to keep the strap taut during travel of the vehicle over 75 ordinary road-way conditions. Should the vehicle wheels travel over a deep rut or de- pression and tend to suddenly carry the axle away from the body and spread the springs, this will be prevented by the inertia of the 80 frictional engagement of the belts with the drums and rollers and then, when after such drop of the axle and vehicle frame, the frame tends to suddenly rebound, the same inertia will prevent such rebound but after 85 such first jerk on the straps, the straps will gradually slip on the drums and will pull against the springs 13 which together with the greatly lessened frictional resistance of the straps will gradually check and absorb 90 the force and will prevent overthrow of the springs and abnormal separation between the vehicle frame and axle, that is, the frame and axle will be gradually restored to nor- 95 mal relative position without shock to the vehicle. Thus any sudden or violent abnor- mal separation between the vehicle body and axis is snubbed and the forces distributed and absorbed by the absorbing devices.

The absorbing device of my invention is 100 of very simple and inexpensive construction, the entire body including the drum, roller supports and spring:barrel being of a single piece of metal and can be readily formed by casting. The device can be applied in 105 different positions to the vehicle. In the ar- rangement shown in Fig. 1, the belt guard rollers are at the side and the belt after leaving the top roller is shown passing over the turn of the belt around the lower roller. 110 This introduces additional friction by the engagement of the belt sections with each

other. The device could be inclined so that there would not be this engagement between the belt sections, or the incline could be such that the engaging surfaces between belt sections would be increased.

5 I do not of course desire to be limited to the precise construction and arrangement shown as modifications are no doubt possible which would still come within the scope of 10 the invention.

I claim as follows:

15 1. A shock absorber for connection with two relatively movable members, comprising a friction drum, a spring extending diametricaly in said drum and having one end anchored thereto, a friction strap encircling said drum adapted to be secured to one of said members, upper and lower rollers journaled on the drum at one side thereof, the 20 inner end of said strap passing from the drum over said lower roller and secured to the free end of said spring, the outer end of said strap passing from the drum downwardly over said upper roller and adapted 25 for connection with the other member.

2. A shock absorber for connection with two relatively movable members, comprising a friction drum, a barrel within the drum extending diametricaly thereof, a compression spring housed within the barrel and abutting against one end thereof, a 30 guide surface at one side of said drum, a friction strap connected with the other end of said spring and extending around said 35 guide surface and then entirely around said drum, said drum being adapted to be secured to one of said movable members and the outer end of said strap being adapted 40 for connection with the other movable member.

3. A shock absorber for vehicles comprising

ing an elliptical drum, a spring positioned within the drum in the major axis thereof, said drum having an outlet at one end, an upper and a lower roller positioned at said 45 outlet, a friction strap secured at its inner end to said spring and extending outwardly through said outlet and around the lower roller and then encircling the drum and engaging with the upper roller, means for securing said drum to a support, and means for securing the outer end of said strap to another support.

4. A shock absorber comprising a drum, a barrel extending diametricaly in said drum, 55 a spring housed within said barrel, said drum having an outlet adjacent one end of said barrel, a friction strap secured to said spring and extending through said outlet, a roller adjacent said outlet, said strap passing around said roller and then entirely around said drum periphery and back across the roller, means for securing said drum to a support, and means for securing the outer end of said strap to a support.

5. The combination with two relatively movable members, of a shock absorber comprising a drum secured to one of said members, a spring within the drum anchored at one end thereto, said drum having a side 70 outlet, a friction strap secured at its inner end to said spring and extending out through said outlet, upper and lower rollers adjacent said outlet, said strap passing around the lower roller and then entirely 75 around the drum periphery and around both said rollers and secured at its outer end to the other movable member.

In witness whereof I hereunto subscribe my name this 18th day of December, A. D., 80 1916.

ALLAN L. McGREGOR.
